UNITED STATES PATENT OFFICE.

EDWARD ERMOLD, OF NEW YORK, N. Y.

BOTTLE-LABELING MACHINE.

1,199,061.

Specification of Letters Patent. Patented Sept. 26, 1916.

Application filed December 5, 1914. Serial No. 875,567.

To all whom it may concern:

Be it known that I, EDWARD ERMOLD, a citizen of the United States, and a resident of the city, county, and State of New York, 5 have invented certain new and useful Improvements in Bottle-Labeling Machines, of which the following is a specification.

This invention relates to bottle labeling machines and the objects of the invention 10 are to provide a bottle labeling machine that is capable of applying labels over the cork or stopper of a bottle so that the cork or stopper cannot be removed without breaking the label.

15 To the accomplishment of the above objects, and to such others as may hereinafter appear, the invention comprises a bottle labeling machine provided with means for folding the ends of a label over the cork or 20 stopper of a bottle, and means for securing the folded ends of said label to the sides of the bottle.

The invention is to be described with reference to the bottle labeling machine shown 25 in my Patent No. 1,023,143 dated April 16, 1912. In the present case the means for operating the pickers, the paste roller and presser-arm are not shown or described, as these features are clearly shown and described in my former patent above referred to, and are well known.

In the drawings: Figure 1 is a front elevation of a portion of a bottle labeling machine made in accordance with my invention, showing the improved parts of the machine, the parts not shown being the same as those shown in my former patent, above referred to. Fig. 2 is a detail view showing a label being placed over the top 40 of a bottle, just previous to the pickers being moved upward. Fig. 3 is a view similar to Fig. 2, showing the pickers moved upward, the folding plates having acted to fold the ends of the label into position, the 45 ends of the label being pressed into engagement with the bottle by the wipers. Fig. 4 is a sectional view on the line 4—4 of Fig. 1. Fig. 5 is a detail view of the engaging end of the presser arm showing one of the 50 folding plates. Fig. 6 is a detail view with parts broken away, showing the action of the wipers when forced into engagement with the neck of a bottle, as seen from above. Fig. 7 is a detail view of a label attached to a bottle after being removed from the machine.

Referring to the drawings, numeral 1 designates the frame of the machine, which is the same as the frame shown in my former patent above referred to. In the 60 present instance the frame is provided with a bracket 21 which supports an adjustable bottle rest 22 which is made of suitable shape to hold a bottle upright as clearly shown in the drawings. 65

A suitable label receptacle similar to that shown in my former patent above referred to, is provided for holding a single pile of labels 44, so that the same can be removed one at a time by means of suitable picker 70 means 52 which are operated in the same manner as the picker means described in my former patent above referred to.

When the pickers remove a label from the bottom of the label receptacle, the pickers 75 carry the label from the position shown in Fig. 1 to that shown in Fig. 2 in which latter position the label is directly over the top of the bottle at which time, in the further operation of the machine, the presser-arm 86 80 moves from the position shown in Fig. 1 to that shown in Fig. 2, so as to press the label down against the top of the bottle. In the further operation of the machine, and while the presser-arm 86 is still holding the label 85 against the top of the bottle, the pickers 52 move upward thereby releasing the free ends of the label which are then forced downward against the sides of the neck of the bottle by the action of the sliding folding plates A as 90 shown in Fig. 3.

The folding plates A as shown in Fig. 5 are each provided with a longitudinal slot B and are slidably retained in position in the end of the presser-arm 86 by means of 95 headed screws C, so that the folding plates A will be free to drop of their own weight as shown in Fig. 3 to fold over the ends of the label, the plates A being made heavy enough to accomplish this purpose. It is also to 100 be noted that the folding plates A are normally in their lowermost position as shown in Fig. 1, but are free to move upward when they come in contact with the top of the label as shown in Fig. 2, in which latter position they remain until after the pickers have moved upward as before referred to. As the folding plates are forced upward when they come in contact with the label it is necessary that they should not be heavy 110 enough to tear the label but only heavy enough to bend the ends of the label down.

ward when the pickers have moved out of the way.

When the folding plates A have operated, as before described, to fold over the ends of the label, suitable wiping means are provided for wiping the ends of the label into contact with the bottle.

The wiping means in the present instance comprise the two wipers D one on each side of the bottle. Each wiper D is pivotally supported upon one end of a lever E, the other end of which passes freely through a hole G in the end of a lever F to permit of the lever E being moved backward against the action of the springs H, the hole G being made large enough to permit the lever E to move up or down a short distance. The lever F is pivoted near its center to one end of a bell crank lever K, the lower end of the lever F being provided with a slot L through which a set screw M secured to the lever K passes for locking the end of the lever F in different positions for adjustment of the wipers. The bell crank lever K is pivoted at its center to a lug N on the frame of the machine and the other end of the lever K is pivoted to one end of a link O, the other end of which is pivoted to a pin P. Both series of levers for the wipers are connected to the pin P, as shown in the drawings, and the pin P is connected to one end of a link Q, the lower end of which is pivoted to one end of a lever R which is pivoted to the frame on the shaft 58. The lever R is provided with a roller S which engages a cam T on the main cam shaft 14 of the machine, the roller S being kept in engagement with the cam T by means of a spring U.

The wipers D are preferably made of soft rubber so as to conform to the shape of the bottle when the same are forced inward to attach the ends of the label to the bottle as shown in Figs. 3 and 6. When the wipers D are forced inward to press the ends of the label against the bottle the wipers are permitted to rock slightly backward and forward against the ends of the label due to the pivoting of the wipers on the levers E, the slightly enlarged holes G in the levers F permitting the levers E controlled by the springs H, to conform to the rocking movement of the wipers.

While the wipers D are permitted to rock or roll slightly when forced into contact with the ends of the label this movement does not tend to displace the position of the ends of the label but only insures the ends of the label being secured firmly to the neck or side of the bottle in the position in which the folding plates A place the ends of the label.

It is ordinarily customary to operate the wipers to give the same a wiping motion such as described in my patent before referred to, but in the present instance this

wiping motion is not desirable for if the wipers D were arranged to move downward after coming in contact with the ends of the label, the label would in most instances tear apart where the label is bent over the top 70 of the bottle. The wiping motion would also not apply the label so well about a circular bead, as shown on the neck of the bottle in Fig. 7, as is the case in the present instance when the wipers are forced only inward and 75 permitted to rock slightly in applying the label as before described.

It is to be noted that the folding plates A only extend downward below the top of the bottle a sufficient distance to insure the 80 proper folding of the ends of the label which extend downward a considerable distance below the ends of the folding plates A to permit of the ends of the label being engaged by the wipers. 85

The end of the presser-arm 86 to which the folding plates A are attached is preferably provided with a rubber seat V to lessen the shock on the bottle, and a sliding rod W controlled by a spring X is also provided for the same purpose. 90

While the present invention has been described with particular reference to the details of construction and as being applicable to the machine set forth in my patent above 95 referred to, the same is not to be considered as limited thereto, as many changes can be made and still fall within the scope of the invention set forth in the following claims:

1. A bottle labeling machine comprising 100 in combination a presser-arm for holding a label in position on the top of a bottle and sliding folding plates secured to the end of said presser-arm for folding the ends of said label over the top of said bottle. 105

2. A bottle labeling machine comprising 110 in combination a presser-arm for holding a label in position on the top of a bottle and folding plates secured to said presser-arm and arranged to drop of their own weight to fold the ends of said label over the top of said bottle.

3. A bottle labeling machine comprising 115 in combination a bottle rest, a label receptacle, oscillatory picker means for transferring labels from said label receptacle to the top of a bottle on said rest, an oscillatory presser-arm for holding a label in position on the top of said bottle, means on said presser-arm for folding the ends of 120 said labels over the top of said bottle, and oscillatory wipers for securing the ends of said labels to said bottle.

4. A bottle labeling machine comprising 125 in combination a bottle rest, a label receptacle, oscillatory picker means for transferring labels from said label receptacle to the top of a bottle on said rest, an oscillatory presser-arm for holding a label in position on the top of said bottle, means on 130

said presser-arm for holding the ends of said labels over the top of said bottle, and independently supported oscillatory wipers for securing the ends of said label to said bottle.

5. A bottle-labeling machine comprising in combination a bottle rest, a label receptacle, oscillatory picker means for transferring labels from said label receptacle to the top of a bottle on said rest, an oscillatory presser-arm for holding a label in position on the top of said bottle, means on said presser-arm for folding the ends of

said label over the top of said bottle, wipers for securing the ends of said label to said bottle, means for operating said picker means, means for operating said presser-arm and means independent of said presser-arm for operating said wipers.

In testimony whereof I have signed this specification in the presence of two subscribing witnesses.

EDWARD ERMOLD.
